UNITED STATES PATENT OFFICE.

JACOB OTT, OF LANCASTER, NEW YORK.

MULTIPLE SHINGLE.

Application filed September 19, 1921. Serial No. 501,748.

To all whom it may concern:

Be it known that I, JACOB OTT, a citizen of the United States, residing at Lancaster, in the county of Erie and State of New York, have invented new and useful Improvements in Multiple Shingles, of which the following is a specification.

This invention relates to the type of multiple shingles or those in which a number of shingle-units are formed in a single strip to save time in laying the same.

One of the objects of the invention is to so cut the multiple shingle-strips as to avoid waste of material.

15 A further object is to construct the two longitudinal edges of the strips symmetrically in such a manner that in case one or more shingle-projections should be torn or broken off at one edge of a strip, the latter 20 can be reversed to conceal the broken edge and present a complete and intact shingle edge at its lower exposed portion, thus avoiding the necessity of discarding such broken shingle strips and effecting an important saving.

Another object of the invention is the improvement of the shingle strips with a view of insuring absolutely tight joints at their ends.

30 In the accompanying drawings:

Figure 1 is a fragmentary plan view of several courses of the improved shingle-strips. Figure 2 is a plan view of a sheet of material, such as ready roofing, showing the 35 method of cutting the strips. Figure 3 is a perspective view of one of the strips. Figure 4 is a transverse vertical section on line 4-4, Fig. 1. Figure 5 is a similar section, showing a defective or worn out shingle 40 withdrawn. Figures 6 and 7 are horizontal sections on the correspondingly numbered lines in Fig. 1.

Similar characters of reference indicate corresponding parts throughout the several 45 views.

As shown in the drawings, the improved shingle-strip is serrated at both longitudinal edges to form a row of substantially V-shaped projections 10 at each edge, representing a corresponding number of shingle units. In the example shown, each strip has four complete shingle-projections at one edge, while its other edge is formed with three complete projections and two half 55 projections arranged at opposite ends there-

of, these half-projections forming complete projections when laid against adjoining strips having similar half-projections. The strips may however be provided with any other suitable number of projections, if 60 desired. The projections at one edge of each strip are staggered with reference to those of the other edge, or, in other words, the projections of one edge are arranged directly opposite the substantially V-shaped 65 recesses 11 of the other edge.

By constructing the shingle-strips in this manner, a number of them can be cut from a single sheet of ready roofing or other appropriate material without waste, by severing the sheet along the dotted zig-zag lines 12 in Fig. 2, these lines extending across the sheet at intervals corresponding to the vertical dimensions of the strips.

Each shingle strip is preferably cut away 75 at its ends, adjacent to one of its longitudinal edges, in the form of angular notches or recesses 13. When such strips are laid end to end on a roof, the vertical edges 14 of their opposing notches abut against each 80 other, as shown in Figs. 1 and 7, while the remaining unnotched end portion of one strip overlaps the corresponding portion of the adjoining strip, as shown in Figs. 1 and 6, producing tight joints which effectually 85 prevent leakage at these points. The edges 14 form stops which limit the extent of overlap of the shingle-strips.

As both edges of the strips have shingle-projections of uniform contour, the strips 90 can be laid to expose either edge. This reversible feature has the advantage that in the event of a projection being broken at one edge, the strip can be reversed to conceal the broken edge under the overlying 95 course of strips, thus avoiding waste of such partly-broken strips.

The shingle strips are usually laid in three courses, as shown in Figs. 1 and 4. The construction of this improved shingle-strip is 100 such that if one should be blown off by a heavy wind, the two remaining courses or thicknesses provide sufficient protection against leakage until it can be replaced, and this is also the case where one or more 105 shingle points or projections are broken off, as above mentioned.

In laying the shingle-strips, they can be 110 readily and properly spaced one above another by bringing the points or projections

of the strips in register with the apexes of the recesses of the underlying course of strips. 15

I claim as my invention:

- 5 1. A reversible shingle-strip, having a row of projections at each of its longitudinal edges forming intervening recesses, the projections at one edge of the strip being disposed directly opposite the recesses of the
- 10 opposite edge, and the projections at both edges being of uniform shape, the strip being provided in each end, adjacent to one of its longitudinal edges, with a notch whose vertical edge is adapted to abut against the

corresponding edge of an adjoining shingle-strip. 2. The combination of adjoining shingle-strips, each having a row of shingle-projections along one of its longitudinal edges, and notches in its ends adjacent to one of such edges, the vertical edges of the notches of adjoining shingle-strips abutting against each other, while the end portion of one strip overlaps the corresponding portion of the adjoining strip, forming partly a butt joint 20 and partly a lap-joint at the adjoining ends of the strips. 25

JACOB OTT.
